UNITED STATES PATENT OFFICE.

DAVID FROELICH, OF NEW YORK, N. Y.

COMBINATION FURNITURE.

No. 853,630.

Specification of Letters Patent.

Patented May 14, 1907.

Application filed January 17, 1907. Serial No. 352,674.

To all whom it may concern:

Be it known that I, DAVID FROELICH, a citizen of the United States, and residing at New York, in the county of New York and State of New York, have invented certain new and useful Improvements in Combination Furniture, of which the following is a specification, such as will enable those skilled in the art to which it appertains to make and use the same.

This invention relates to combination furniture, and the object thereof is to provide an improved device of this class designed for use both as a bed and a couch, and which is also simple in construction and operation, easily manipulated or changed from one position to another and which is also strong and durable and comparatively inexpensive.

This invention is an improvement on that described and claimed in U. S. Letters Patent granted to me April 25, 1905, No. 788,311 and is fully disclosed in the following specification, of which the accompanying drawing forms a part, in which the separate parts of my improvement are designated by suitable reference characters in each of the views, and in which:—

Figure 1 is an end view of my improved combination article of furniture and showing the parts folded for use as a couch; Fig. 2 a perspective view showing the parts extended for use as a bed; Fig. 3 an end view of the device as shown in Fig. 2 and indicating the operation of changing the parts from the position shown in Fig. 1 to that shown in Fig. 2; Fig. 4 a side view of the top part of one of the front legs or posts of the main frame and showing the method of connecting the main and supplemental frames of the device; Fig. 5 a section on the line 5—5 of Fig. 4; and, Fig. 6 a section through the top of the rear corner of one of the legs or posts of the main frame on the line 6—6 of Fig. 2 and showing the method of connecting an auxiliary frame with the top portion of the main frame.

In the practice of my invention, I provide a main frame *a* composed of corner posts or legs *a*², parallel side rods *a*³ and transverse end rods *a*⁴, and in practice the parallel side rods *a*³ and transverse end rods *a*⁴ are preferably connected with the corner posts or legs *a*² about midway thereof by means of ordinary four-way couplings *a*⁵, and I also provide longitudinal bed frame strips, springs

or similar devices *a*⁶ which are connected with the transverse end rods *a*⁴, and while I have shown the parts *a*², *a*³ and *a*⁴ as composed of ordinary tubular rods, it will be understood that the same may be composed of angle rods or bars if desired, or of any other suitable material. I also provide a supplemental frame *b* composed of transverse end members or rods *b*² having end portions *b*³ which extend therefrom at an angle thereto, and the transverse end members or rods *b*² are connected by parallel longitudinal rods *b*⁴ for which purpose ordinary elbow couplings *b*⁵ are employed in the form of construction shown.

A part of one of the front corner posts or legs *a*² of the main frame is shown in Fig. 4, together with one of the end portions *b*³ of one of the transverse rods or members *b*² of the supplemental frame *b*, and in practice the parts *b*³ at one side of the supplemental frame fit between the top portions of the end legs or posts at the front side of the main frame and are connected therewith as shown in Figs. 4 and 5 and as indicated in Figs. 1, 2 and 3. For this purpose, I secure to the top part of the front posts or legs *a*² of the main frame vertically arranged keepers *c* which are substantially yoke-shaped in cross section, and the vertically arranged cross head parts *c*² of which are provided with vertical slots *c*³ adapted to receive headed lugs or projections *c*⁴ connected with the parts *b*³ of the supplemental frame, and with this construction it will be apparent that the supplemental frame *b* may be swung out into the position shown in Fig. 2, when it is desired to use the article of furniture as a bed, or may be folded inwardly into the main frame as shown in Fig. 1 when it is desired to use the article of furniture as a couch. The supplemental frame *b* also comprises an auxiliary top frame or portion *d* composed of parallel side bars *d*² and transverse end bars *d*³, and the bars *d*² and *d*³ are connected by a suitable network *d*⁴ of spring material in the usual manner, and the bars *d*² and *d*³ are preferably composed of angle iron and the parts *b*³ of the supplemental frame *b* fit in the corners of the auxiliary frame *d*, and said frames *b* and *d* are secured together at said corners in any desired manner, and as thus constructed it will be seen that the frames *b* and *d* make up the complete supplemental frame of the combination article of furniture which is adapted to

be folded into the main frame as shown in Fig. 1 or to be extended as shown in Fig. 2. The main frame *a* of the device is also provided with an auxiliary frame *e* composed of 5 parallel side bars *e*² and transverse end bars *e*³, and said frame is provided with the usual bed spring material *e*⁴, and the side bars and end bars of the auxiliary frame *e* of the main frame *a* are preferably composed of angle 10 iron and the tops of the corner posts or legs *a*² of the main frame *a* fit in the corners of the frame *e* when the latter is folded over the frame *a* as shown in Figs. 1, 2 and 3, and the frame *e* is pivoted to the tops of the rear corner posts or legs *a*² of the frame *a* as shown 15 at *f*, this construction being best shown in Fig. 6.

The supplemental frame *b*, or the part *b* of the supplemental frame which is pivoted to 20 the front corner posts of the main frame is provided with supports adapted to support it when in an extended position as shown in Figs. 2 and 3. These supports consist of two sets of legs *g* connected by transverse bars *g*² 25 and pivotally connected with or hinged to the opposite end portions of the rods *b*⁴, and double link members *g*³ connected with the rods *b*⁴ and with the leg members *g* in such manner that when the supplemental frame 30 is extended as shown in Figs. 2 and 3, the leg members *g* may be lowered to support said frame, and when the supplemental frame is folded within the main frame as shown in Fig. 1, the said leg members may be folded 35 so as to rest within said supplemental frame.

In the form of construction shown, the top of the supplemental frame is below the top of the main frame when the parts are extended for use as a bed as clearly indicated in 40 Figs. 2 and 3, and in practice, I provide the supplemental frame with a mattress *h* which is thicker than the mattress *h*² employed on the main frame.

In order to fold the supplemental frame 45 into the main frame as shown in Fig. 1, the auxiliary part *e* of the main frame must be folded backwardly as indicated in dotted lines in Fig. 3, and this operation must also be repeated in extending the supplemental 50 frame, but when the supplemental frame is folded into the main frame as shown in Fig. 1 the auxiliary part *e* of the main frame is folded thereover, and when the supplemental frame is extended as shown in Fig. 2 the 55 auxiliary part *e* of the main frame is folded over onto the top of said main frame. When the supplemental frame is folded into the main frame as shown in Fig. 1, the mattress *h* rests on the strips *a*⁶ of the main frame and 60 the supplemental frame rests on said mattress, and if desired any amount of bedding or bedding material may be placed in the

supplemental frame or between the parts *b* and *d* of said frame.

It will be observed that the supplemental 65 frame *b* may be entirely separated from the main frame *a* by simply raising the supplemental frame out of the lock formed by the parts *c*³ and *c*⁴, the former being dropped into the latter in order to connect said frames and 70 when the said frames are thus disconnected they may be used independently of each other or both may be used separately as couches, divans or small beds.

Having fully described my invention, what 75 I claim as new and desire to secure by Letters Patent, is:—

1. A combination article of furniture adapted to be used both as a bed and as a couch, comprising a main frame provided 80 centrally and horizontally with supports, a supplemental frame detachably pivoted in the front top portion of the main frame by means of vertically arranged slotted keepers secured to the front corner posts of the main frame, 85 and headed lugs or projections secured to the corresponding parts of the supplemental frame and adapted to enter said vertically slotted keepers, said supplemental frame being also adapted to be folded into the main 90 frame and to be extended in front thereof and provided with mattress springs and between its ends with folding legs, the main frame being also provided with an auxiliary frame which is hinged to the tops of the rear 95 corner posts thereof and which is adapted to be folded over said main frame and rest on the front corner posts thereof, said auxiliary frame being also provided with mattress springs. 100

2. A combination article of furniture adapted to be used both as a bed and a couch, comprising a main frame provided centrally and longitudinally with springs or supports, a supplemental frame detachably pivoted in 105 the front top portion of the main frame and provided with mattress springs and between the ends thereof with foldable legs and adapted to be folded into the main frame and to be extended in front thereof, the main 110 frame being also provided with an auxiliary frame which is hinged to the tops of the corner posts thereof and which is adapted to be folded over and rest on the corner posts thereof, said auxiliary frame being also provided 115 with mattress springs.

In testimony that I claim the foregoing as my invention I have signed my name in presence of the subscribing witnesses this 15th day of January 1907.

DAVID FROEHLICH.
